UNITED STATES PATENT OFFICE.

HARRY A. STONE, OF PHILADELPHIA, PENNSYLVANIA, ASSIGNOR TO FOLDING UTILITIES CORPORATION, OF NEW YORK, N. Y., A CORPORATION OF NEW YORK.

FOLDABLE OR COLLAPSIBLE CHAIR.

1,263,717.

Specification of Letters Patent. Patented Apr. 23, 1918.

Application filed September 24, 1915, Serial No. 52,405. Renewed September 14, 1917. Serial No. 191,503.

To all whom it may concern:

Be it known that I, HARRY A. STONE, a citizen of the United States, residing at Philadelphia, county of Philadelphia and 5 State of Pennsylvania, have invented certain new and useful Improvements in Foldable or Collapsible Chairs, of which the following is a specification.

This invention relates to foldable or collapsible chairs.

My object is to provide a chair of improved construction which can be collapsed or folded into compact condition or readily extended and set up for use, wherein the 15 foldable or collapsible legs and their braces, the seat portion, and the back will be of novel construction and the parts thereof combined in an improved manner.

My object, particularly, is to obtain lightness with strength, durability, compactness when folded or collapsed, neatness of appearance, inexpensiveness of manufacture and comfortableness when in use.

One form of the braces for the legs is 25 substantially that set forth in the application of Carleton W. Smith, renewal No. 112,478, filed July 31, 1916, for foldable or collapsible stands, but in lieu of such bracing, I may provide a chain or wire bracing 30 combined with the legs in an improved manner, and the invention possesses features and combinations of parts not found in the aforesaid Smith application.

While my invention is preferably carried 35 out in a chair having a back and by the provision of only three legs, the invention may be embodied in a chair having four legs, and without a back; or, it may be embodied in the form of a table, inasmuch as the top or 40 seat cooperates with the legs in an improved and novel manner in all forms of the invention, whatever use the device may be put to. Further, many modifications may be resorted to in carrying out the different inventive 45 ideas and I do not, therefore, limit myself to the details of construction hereinafter specified and disclosed in the drawings, all of which are to be considered as illustrative, rather than restrictive, of the scope of the 50 invention.

In the accompanying drawings:—

Figure 1 is a perspective of the chair set up and ready for use;

Fig. 2, a detail rear elevation showing the 55 back;

Fig. 3, a view of the chair when folded;

Fig. 4, a detail of one corner of the seat;

Fig. 5, a detail of the front portion of the seat;

Fig. 6, a detail of one of the joints of a 60 brace;

Fig. 7, a detail showing how one of the corners of the seat is held by a hook;

Fig. 8, a detail of one of the corner hooks for the rear legs; 65

Fig. 9, a modification of Fig. 8;

Fig. 10, a detail of the hook on the front leg;

Fig. 11, a detail of one panel or pair of legs showing another form of bracing; 70

Fig. 12, a perspective showing the invention embodied in a table or stool; and

Fig. 13, a view of a modified support for the front of the seat.

Preferably three legs 1 are employed, but 75 four may be used if desired, either for the purpose of providing a chair, with or without a back, or a stool or table as shown, for instance, in Fig. 12.

The legs 1 may be of angle iron, as shown 80 in Figs. 1 and 12, or tubular, as shown at 1^a in Fig. 11.

Referring to Figs. 1 and 12, the legs 1 are connected by upper and lower jointed lateral braces 2 and 3 pivoted to the legs at 4 and 85 having their sections pivotally connected at 5 and provided with stop devices 6 of the same general construction as set forth in the application of Carleton W. Smith, renewal No. 112,478 heretofore referred to. 90

Crossed tension braces or linkages 7 are connected to the pivots 4 and the sections thereof are jointed at 8 in a manner substantially similar to the crossed tension braces of the Smith application, but I prefer to provide these tension braces with stop devices 9 such as employed at 6. 95

As an improvement on the crossed tension braces, I provide the construction shown in Fig. 11, where there is represented 100 but a single panel of the chair, table or stool support, whether embodied in a three-legged or four-legged structure. The braces 2^a, 3^a, are provided with stop devices 6^a and are adapted to "break" in opposite directions, as shown by dotted lines, whereas the braces 2 and 3 are adapted to "break" toward each other. Chains, wires, or other flexible and non-rigid crossed tension members 10 are connected to the legs, preferably 105 110

at the pivotal points 4^a of the braces 2^a, 3^a. The use of wires, chains or equivalent flexible cross tension members at 10, very materially reduces the cost of construction 5 over that of the braces 7 and has another advantage in that these braces are adapted to "break" or yield at all points so that they may be very easily collapsed or extended. The braces 10 of Fig. 11 may be used on 10 any form the invention may assume in substitution for the braces 7. For instance, in either Fig. 1 or Fig. 12, the braces 7 may be dispensed with and braces 10 substituted.

Whichever form of bracing is employed, 15 the legs can be extended, as shown in Figs. 1 and 12, or moved bodily toward each other into the collapsed condition shown in Fig. 3, in which state the device is folded in compact and collapsed condition, whatever form 20 it may assume and whether provided with a back or not.

Referring to Figs. 1 and 2, the seat 11 is of cloth, canvas or other pliable or flexible material of sufficient stoutness and strength, 25 being provided at its rear corners with eyelets or gromets 12, such as shown, for instance, in Fig. 7. The seat 11 is flexible throughout except at its front edge, where it is provided with a crosswise extending 30 sheath or pocket 13 which has an opening or exposed portion 14 intermediate its ends (Fig. 5). Contained within the sheath or pocket 13 is a rod 15 which runs substantially the full length thereof and whose central portion is exposed at 15^a. Secured to the upper end of the front leg 1 is a hook 16 (Fig. 10) which may be made of a piece of metal provided with parts 16^a riveted to the sides of the leg 1. The hook is adapted 40 to engage the exposed portion 15^a of the rod 15 after the gromets 12 have been slipped over hooks 17 of the members 18 (Fig. 8) which are fastened to the upper ends of the rear legs 1 by rivets or fastenings 19 45 passing through holes 20. The seat 11 is, therefore, completely detachable from the hooks 16 and 17. I may, however, make one of the hooks 17 in the form of a closed loop 17^a, as shown in Fig. 9 to which the 50 gromet 12 at that corner of the seat is permanently connected, as shown in Fig. 9. If this construction is employed, the seat 11 cannot become detached or lost. Whichever form of hook 17 or 17^a is employed, the 55 seat 11 is intended to be disengaged from the remaining hook 17 and front hook 16 so that it may be wrapped around the collapsed legs and back rods, as shown in Fig. 3.

60 Pivoted to the rear faces of the rear legs 1, as for instance, on the upper pivots 4, are foldable rods 21 which can be disposed downwardly alongside the rear legs 1 or extended into upright position, as shown in 65 Figs. 1 and 2. These rods are held by hooks

or clips 22 which may be a part of the fittings or members 18 for cheapness of manufacture, as shown in Figs. 8 and 9, but they can be separately attached to the rear legs 1. A fabric or flexible back 23 connects the 70 upper ends of the rods 21 and is of any suitable width and provided at its ends with sheaths or pockets 24 which receive the upper ends of said rods and are provided with button-holes 25 to engage studs or buttons 26 on the rods to prevent accidental detachment. 75

The seat 11 is provided with snap fasteners 27 and the back 23 has snap fasteners 28, affording means whereby, after the seat and back have been wrapped around the collapsed structure, they may be fastened in bound condition thereabout, as shown in Fig. 3. 80

In the table construction shown in Fig. 12, the legs 1 and braces 2, 3 and 7, are of the same form as heretofore set forth. Preferably four legs are provided. The top 11^a engages hooks 17^b at the upper ends of the legs or at least three of them. The fourth leg may have a closed hook 17^c such as shown at 17^a in Fig. 9, or, a hook such as 17^b may be used. The tension is such that the top 11^a is held taut when the legs are in extended and set-up condition. This 90 form of the invention is also adapted for use as a stool if made in smaller sizes. 95

In Fig. 13 I have shown a modified support for the front of the seat 11^d. The rod 15 is dispensed with and eyelets or gromets 11^e are provided at the front corners of the seat. The chair is otherwise constructed substantially as in Fig. 1 and as previously described. To the front leg 1^d are pivoted at 40^a two foldable braces 40 having hooked upper ends 41 adapted for reception in the gromets 11^e. A foldable brace 42 pivoted to one of the braces 40 at 43 is adapted to detachably engage the other brace at 44. The upper end of the leg 1^d is slotted at 44^a 105 to receive the brace 42. When folded, the braces 40 lie alongside the leg 1^d and the brace 42 alongside the brace 40 to which it is pivoted at 43. 110

In the claims when I refer to a "chair," I 115 intend to cover chairs, stools or seats with or without backs, and tables or stands; also equivalent structure, and I do not thereby limit myself, except where specifically set forth, to the provision of a back.

Having thus described my invention, what I claim as new and desire to secure by Letters Patent, is:—

1. In a foldable or collapsible chair, the combination with three foldable supports, 125 of a multi-cornered flexible or foldable seat, having a sheath at its front edge, engaging devices for connecting the rear corner portions of the seat to the two respective rear supports, a rod carried in the sheath at the 130

front portion of the seat, and means on the front support adapted to detachably engage with an exposed central portion of said rod.

2. A foldable or collapsible chair comprising, in combination, relatively bodily movable foldable legs, foldable braces connecting the legs, a foldable seat, and a foldable back, embodying independent pivoted foldable rods adapted to be swung upwardly, or downwardly, alongside said legs, a detachable back-piece connecting said rods, and retaining devices for holding the rods in raised position, said back piece preventing the rods from becoming freed from said retaining devices.
3. A foldable or collapsible chair comprising, in combination, relatively bodily movable foldable legs, foldable braces connecting the legs, a foldable seat, and a foldable back embodying independent pivoted foldable rods adapted to be swung upwardly, or downwardly alongside the legs, a flexible or pliable back-piece having pockets or sheaths adapted to receive the free ends of the rods, and buttons and eyelets for detachably connecting the sheaths to the rods, and retaining devices for holding the rods in raised position, said back piece preventing the rods from becoming freed from said retaining devices.
4. In a chair, a foldable back comprising foldable rods, retaining devices for holding the rods in upright position; and a flexible or pliable back-piece detachably connected

to the rods, said back piece preventing the rods from becoming freed from said retaining devices.

5. In a chair, a foldable back comprising foldable rods, hook clips for holding the rods in upright position, and a detachable back piece connected to said rods and adapted to hold them engaged with said hook clips.

6. In a chair, a foldable back comprising foldable rods, hook clips for holding the rods in upright position, and a back-piece of flexible or pliable material having sheaths or pockets adapted to detachably receive the free ends of the rods, said back piece being adapted to hold the rods in engagement with the hook clips.

7. A folding or collapsible chair comprising relatively foldable legs, braces connecting the legs, a seat of flexible or pliable material adapted for connection to the legs when the latter are extended and carrying two-part snap fasteners, whereby said seat may be fastened around the legs when the latter are folded, and a foldable back comprising foldable rods and a back-piece of flexible or pliable material connecting the rods and carrying two-part snap fasteners whereby said back-piece may be fastened after being wrapped around the legs when the latter are folded.

In testimony whereof I hereunto affix my signature.

HARRY A. STONE.
